DESIGN FOR A CASE FOR A CLOCK

Darrell B. Linville, Ephrata, Wash.

Application November 18, 1935, Serial No. 59,641

Term of patent 14 years

To all whom it may concern:

Be it known that I, Darrell B. Linville, a citizen of the United States of America, residing at Ephrata, in the county of Grant and State of Washington, have invented a new, original, and ornamental Design for a Case for a Clock, of which the following is a specification, reference being had to the accompanying drawing, forming part thereof, wherein:

Figure 1 is a front view of a case for a clock, showing my new design.

Figure 2 is a top plan view of the same.

I claim:—

The ornamental design for a case for a clock as shown.

DARRELL B. LINVILLE.
